UNITED STATES PATENT OFFICE.

CHARLES H. EMERSON, OF PORTLAND, MAINE.

GAME APPARATUS.

1,055,151.

Specification of Letters Patent.

Patented Mar. 4, 1913.

Application filed July 8, 1911. Serial No. 637,553.

To all whom it may concern:

Be it known that I, CHARLES H. EMERSON, a citizen of the United States, residing at Portland, in the county of Cumberland and State of Maine, have invented new and useful Improvements in Game Apparatus, of which the following is a specification.

My invention relates to a game apparatus comprising a series of movable cards or blocks each bearing a letter of the alphabet and a chance controlled device operated to select a series of cards from which words are to be formed, the object being to find answers to questions from a number of letters selected by the chance controlled device.

The invention consists in the novel features hereinafter described and particularly pointed out in the appended claims.

Referring to the drawings forming a part of this specification, Figure 1 is a plan view of a device or apparatus embodying my invention. Fig. 2 is a longitudinal section of the same on line 2—2 of Fig. 1, and Fig. 3 is a plan view of the chance controlled device with the upper wall or cover removed.

A indicates a board or support on which is mounted a chance controlled device consisting of a box or receptacle B containing a number of differently colored balls C. Said box is shown as having its top wall b and bottom wall b' spaced apart so that the balls C will be free to roll about in the box without riding upon or over each other. Projecting from each of the opposite side walls b² and b³ are wedge-shaped blocks b⁴ which insure a thorough mixing of the balls, when they are moved about by tilting or shaking the box, so as to reduce liability of repetition of a particular arrangement of the balls in successive operations of the device.

In the bottom wall b' of the receptacle there is a pocket d adjacent the side wall b², and in said side wall adjacent said pocket there is a light opening d'. As shown, the pocket d is adapted to receive three balls C, and opposite said pocket there is a sight opening d² through which the balls in the pocket may be seen. The top wall of the box is preferably made of glass covered with paper or cloth, the latter being cut away to form the sight opening. Angularly arranged within the pocket d, is a mirror d³ which reflects light from the opening d' through the balls C to the sight openings d². The balls are preferably made of different

colored glass or other transparent or translucent material so that the balls in the pocket d will appear to be illuminated with their colors brilliantly displayed. Without the light opening i. would be difficult to quickly distinguish the colors, and while the balls would be illuminated to a degree without the mirror d³, the latter adds brilliance to the light which appears to come from the balls instead of through them.

When the box or receptacle is tilted in the proper direction three of the balls C will roll into the pocket d, and will be retained therein so long as the box is not tilted in a direction to dislodge them. Some of the balls are colored red, some blue and others white, so that in repeated or successive operations of the device different color combinations will be formed by the three balls which roll into the pocket d and which may be seen through the sight opening d². The various color combinations which may be thus formed represent letters of the alphabet which are to be used to form words. Near the left hand margin of the board A is an index E, showing the color combination for each letter of the alphabet, this being indicated by red, white and blue dots representing the visible balls in the chance controlled device. As shown, white, blue and red designate the letter A. Blue, red and blue designates the letter B, and so through the alphabet, each color combination indicating or designating a different letter.

The board A is provided with 26 card holders or pockets f, each marked with a letter of the alphabet, and each containing a number of cards F bearing the letter which is stamped on the pocket or holder. The holder or pocket marked "A" contains a number of cards F bearing the letter A, the holder marked "B" contains a number of cards F bearing the letter B and so on throughout the entire series of pockets. The board A is also provided with grooves G into which cards F may be inserted, these grooves being formed by strips of wood or other material g, secured to the board and having under-cut edges g' which lap over and retain cards that may be slipped or slid between the strips as clearly illustrated in Figs. 1 and 2.

In using the device, the operator faces the light so that the balls in the chance device will be properly illuminated. The

board A is tilted or moved in various directions to thoroughly mix the balls C in the box or receptacle B, and is then tilted to permit three of the balls to roll in the ball pocket d. The color combination formed by these three illuminated balls will indicate a certain letter which is determined by the index E. A card bearing the indicated letter is removed from its pocket or holder 10 f, and after a number of cards have been thus selected, the operator proceeds to form words from the letters on the selected card which may serve to answer a question previously asked by the operator.

15 It is to be understood that various changes in the details and in the general form of the apparatus may be made without departure from the main features of my invention.

20 Having thus described my invention, what I claim is:

1. A game apparatus comprising a board or support, a chance controlled device mounted thereon consisting of a box or receptacle with a series of differently colored balls therein, one of the walls of said box being provided with a pocket for receiving a fixed number of balls less than the total number of balls within the receptacle, a 25 sight opening through one of the walls of the box opposite said pocket, a series of card holders mounted on said board each containing a plurality of movable cards bearing a letter of the alphabet, and an index show-

ing color combinations that may be formed 35 by the balls that may be seen through the sight opening of the chance controlled device, each color combination of the index indicating a letter of the alphabet.

2. A chance controlled device comprising 40 a box or receptacle containing a series of differently colored balls, one of the side walls of the receptacle being provided with a light opening, a pocket in the bottom wall adjacent said opening adapted to receive a fixed number of balls, and a sight opening in the top wall of the receptacle opposite said pocket.

3. A chance controlled device comprising 45 a box or receptacle containing a series 50 of differently colored translucent balls, a light opening in one of the side walls of the receptacle, a pocket in the bottom wall of the receptacle adjacent said opening, adapted to receive a fixed number of balls, a 55 sight opening in the top wall of the receptacle opposite said pocket and a mirror angularly arranged in said pocket to reflect the light from said light opening to the sight opening for the purpose specified. 60

In testimony whereof I have hereunto set my hand in presence of two subscribing witnesses.

CHARLES H. EMERSON.
